LOCK-STITCH SEWING MACHINE

Andrew B. Clayton, Elizabeth, N. J., assignor to
 The Singer Manufacturing Company, Elizabeth, N. J., a corporation of New Jersey

Application January 1, 1945, Serial No. 570,926

16 Claims. (Cl. 112—181)

This invention relates to lock-stitch sewing machines and it has as a primary object to improve the sewing qualities of such machines, especially when operating at high speeds.

It is well known that many sewing machines which will operate satisfactorily at speeds in the neighborhood of 4,500 stitches per minute, will develop peculiarities and faults, such for example as the skipping of stitches, uneven stitching, irregular feeding and the breaking of thread, when operated at speeds of 5,000 stitches or more per minute. The reasons for these faults or failures are extremely difficult to discover because of the fact that they do not occur constantly and when they do occur it is at such high speeds and in such inaccessible places that the particular cause at the time of failure cannot be perceived.

Heretofore, attempts have been made to solve these mysteries of sewing machines by the use of stroboscopes and high speed moving picture cameras, without complete success.

Probably the difficulties inherent in obtaining perfect sewing can best be understood by analyzing the stitch formation of a high speed lock-stitch sewing machine of the rotary hook type. To make a single lock-stitch, the needle descends through the work and carries with it the needle thread. As the needle starts to rise, it throws out a loop of needle thread, which loop is entered by the loop-taker beak travelling at a speed of over 650 inches per second. The loop-taker has journaled therein a bobbin-case, carrying a bobbin of lower thread which, in the formation of a lock-stitch, must be passed, as a mass, through the needle-thread loop. This is effected by the loop-taker spreading the needle-loop and passing it bodily around the bobbin-case and the bobbin therein. In conventional sewing machines, this necessitates the passage, through the eye of the needle, of approximately 4½ inches of thread. After the loop has been passed about the bobbin-case all of the slack thread has to be taken up by pulling the surplus thread back through the eye of the needle. This is done by a variable speed take-up mechanism. Thus the cycle for each stitch includes the drawing of approximately 4½ inches of thread through the eye of the needle, first in one direction to spread the loop and pass it about the bobbin-case and then in the opposite direction to take up the slack and set the stitch, thereby causing the passage of approximately 9 inches of thread through the needle-eye for each individual stitch. When the machine is operating at 5,000 stitches per minute, which is not uncommon, 45,000 inches of thread

is passed through the needle-eye per minute, (i. e. 750 inches per second) at a varying speed, which reaches a maximum of over 1,700 inches per second when the take-up is moving at its highest speed.

5 In sewing relatively thin or light weight material with stitches of medium length, i. e. sixteen stitches to the inch, each particle of thread passes through the needle-eye approximately 100 times (50 down and 50 up) before that particle of thread is incorporated in the seam.

It will readily be understood that this repeated reaving of the thread back and forth through the eye of the needle, at the high speed at which the thread travels, tends to fray and weaken the thread with the result that any undue strain on the thread, such as may be caused by friction of one thread on the other, or friction of the threads on the work, or on the wall of the needle-hole in the throat-plate of the machine, can result in breaking of the thread, skipping of

10 stitches, impairment of the seam, or other failure of the machine properly to perform its intended function.

15 25 A contributing cause to such failure is the fact that sewing thread is not entirely uniform, varying in both thickness and strength and therefore containing certain weak spots. Also some threads, of the cheaper varieties, contain knot-like slubs which, in passing through the thread tension, place additional strain on the thread, thereby sometimes resulting in thread breakage, especially if the thread has been weakened.

20 35 Thread breakage from this cause is proportionate to the amount of tension placed on the thread; the lighter the tension, the more freely will the thread containing the slab pass therethrough, and, therefore, the less will be the thread breakage.

30 40 It will also be understood that any undue retardation in the movement of the thread, such as may be caused by excessive friction between the needle and bobbin threads, or between those threads and parts of the sewing machine, such as for example as the wall of the needle-hole, will interfere with the proper action of the take-up in setting the stitch and therefore will result in uneven sewing. Such conditions are, of course, exaggerated when a thickened portion of the thread, or a slab, passes through the stitch-forming mechanism.

45 50 In conventional high speed lock-stitch sewing machines, the needle reciprocates in a vertical path perpendicular to the upper surface of the throat-plate, through the needle-hole in the

throat-plate and directly toward the axis of rotation of the loop-taker, which axis extends lengthwise of the machine base and transversely of the line of seam formation. A good example of this type of sewing machine is shown in the United States patent of Kessler, No. 2,085,699, June 29, 1937.

In machines of this type, one-half of the loop-taker and one-half of the bobbin of lower thread is located rearwardly of the line of reciprocation of the needle. In this arrangement, the bobbin thread emerges from the bobbin-case at a point rearwardly of and substantially in the horizontal plane of the axis of rotation of the loop-taker. From its point of emergence the bobbin thread extends upwardly and forwardly to the lower end of the needle-hole in the throat-plate.

Feed of the work pulls on the bobbin thread and, due to the location of its point of emergence from the bobbin-case, tends to turn the bobbin-case and its carrier-element in a direction opposite to the direction of rotation of the hook, thereby tending to open a gap between the bobbin-case carrier element and its rotation-restraining lug, thus permitting escape of the cast off needle-loop, as is well understood in the art. From the upper end of the needle-hole, the bobbin thread is drawn rearwardly by the movement of the work.

Thus the bobbin thread is snubbed about and bears with considerable pressure against the rear wall of the needle-hole. During the formation of each stitch, the needle-thread loop is required to be pulled up between the bobbin-thread and the wall of the needle-hole about which the bobbin-thread is snubbed, thereby producing a sawing action between the threads. The greater the pressure of the bobbin-thread on the wall of the needle-hole the greater will be this sawing action and the more likelihood of thread failure. Also the greater the resistance the needle-thread loop has to overcome in passing between the bobbin-thread and the wall of the needle-hole the greater will be the tension required on the needle-thread to insure that the take-up will tighten and set the stitch without stealing thread from the supply.

From the foregoing it will be apparent that any improvement in, or arrangement of, the parts which reduces snubbing, and/or reaving actions on the thread, or permits the use of a lighter needle-thread tension for a given tension on the bobbin thread, will reduce thread breakage and improve the sewing qualities of the machine.

This has been accomplished by a novel arrangement of the needle and the loop-taker relative to the horizontal work-support of the machine and to the needle-hole in the throat-plate.

In accordance with the preferred embodiment of the present invention, the axis of the loop-taker is arranged forwardly of the needle-hole so that the lead of the bobbin-thread extends more nearly vertical to the needle-hole, thereby greatly reducing the snubbing action of the bobbin-thread about the rear wall of the needle-hole. Consequently the pressure of the bobbin-thread on the wall of the needle-hole is lessened materially, which facilitates the passage of the needle-thread loop therebetween, with a considerable reduction in the sawing action between the threads.

Preferably, the needle-bar and the needle carried thereby are tipped backwardly away from the operator so that the needle in its downstroke is inclined downwardly and forwardly, thus maintaining the desirable condition of passing through the needle-hole and directly toward the axis of rotation of the loop-taker. The needle-thread

loop is seized by the loop-taker at a point in the path of the loop-taker beak substantially at one side of the highest point of said beak and while the beak is travelling between its highest and lowest positions.

With the above and other objects in view, as will hereinafter appear, the invention comprises the devices, combinations and arrangements of parts hereinafter set forth and illustrated in the accompanying drawings of a preferred embodiment of the invention, from which the several features of the invention and the advantages attained thereby will be readily understood by those skilled in the art.

In the drawings,

Fig. 1 is a longitudinal sectional view of a lock-stitch sewing machine embodying the present invention.

Fig. 2 is a side elevation of the bracket-arm head of the machine.

Fig. 3 is a left end view of the machine illustrated in Fig. 1, with the face plate removed.

Fig. 4 is a vertical sectional view taken substantially on the line 4—4 of Fig. 1.

Fig. 5 is a plan view of the rotary hook of the present machine showing it associated with its rotation-restraining means.

Fig. 6 is a diagrammatic view illustrating the improved arrangement of the elements of the stitch-forming mechanism, relative to each other and to the needle-hole.

Referring more specifically to the drawings, the invention is illustrated as embodied in a sewing machine comprising a base 1, affording a horizontally disposed work-supporting plate 2, having a front edge *f* proximate to the operator, and a rear edge *r* remote therefrom. Preferably a portion 3 of the work-support is removably secured to the main portion thereof and is provided with a needle-hole *n*, and slots *s* for the passage of a conventional feed-dog *d*, later to be referred to. The portion 3 is commonly known as the "throat-plate" of the machine but for the purpose of this disclosure may be considered broadly as a part of the work-support.

Rising from the right end of the work-support 2 is a hollow standard 4 having formed integrally therewith an overhanging bracket-arm 5 carrying, at its free end, a hollow bracket-arm head 6 which is normally closed by a removable face-plate 6^a. Journaled lengthwise of the arm 5 in bearings 5^a, 5^b and 5^c is a main or needle-bar driving shaft 7 carrying, at its rear end, a combined belt-pulley and hand-wheel 8 which may be driven from any suitable source of power.

Journaled in the base 1, beneath the work-supporting plate 2, is a rotary loop-taker driving shaft 9 which carries, at its forward end, a loop-taker of the rotary-hook lock-stitch type, designated generally as L. The loop-taker comprises the usual rotary hook *h*, bobbin-case carrier element *e* journaled therein but held against rotation, bobbin-case *c* non-rotatably mounted in the element *e*, and a bobbin *b* of lower thread in the bobbin-case. As shown most clearly in Figs. 5 and 6 the bobbin-case carrier-element is formed at its needle-loop cast-off side with a needle-loop controlling flange 10 in the upper portion of the front face of which is formed a rotation restraining notch 11 entered by a tongue 12 of a rotation-restraining bar 13 mounted on the under side of the work-support 2.

The loop-taker driving shaft 9 is journaled in bearings 14 and 15 carried by the base 1 and is driven from the main shaft 7, at a ratio of

two-to-one, through the medium of a first pair of bevel gears 16, 17, a shaft 18 journaled lengthwise within the standard 4, and a second pair of bevel gears 19, 20. Thus the loop-taker is given two rotations for each rotation of the main shaft 7.

At its forward end the shaft 7 has secured to it a crank-disk 21 carrying a crank-pin 22, which, through a link 23 and collar 24, transmits reciprocatory motions to an inclined needle-bar 25 slidably mounted in bearings 26 and 27 in the head 6. At its lower end, the needle-bar carries an eye-pointed needle N which, in the formation of stitches, cooperates with the loop-taker L, before mentioned. The crank-pin 22 also actuates a link-type needle-thread take-up device, designated generally as 28, which cooperates with a manually regulatable needle-thread tension 29 in controlling the needle thread and in tightening and setting the stitch. Also mounted in the head 6, substantially parallel to the inclined needle-bar 25, is a spring-depressed presser-bar 30 which carries, at its lower end, a presser-foot 31.

The work is advanced past the stitch-forming mechanism by a four-motioned work-feeding mechanism including a feed-drive rock-shaft 32, and a feed-lift rock-shaft 33 each journaled in bearings depending from the work-plate 2. The feed-drive rock-shaft has upstanding arms 34, the upper ends of which are pivotally connected at 34^a, to the rear end of feed-bar 35 carrying the serrated feed-dog d. Preferably the arms 34, of the feed-drive rock-shaft, are so arranged that their pivotal connection with the feed-bar 35 is located rearwardly of and never intersects a vertical plane containing the axis of the shaft 32. Thus, during endwise movements of the feed-bar, the pivotal point 34^a is, at all times, either rising or falling. This produces the desirable effect of raising the rear end of the feed-dog in advance of the forward end thereof and causing the rear end of the feed-dog to drop quickly near the end of the feeding stroke.

At its forward end, the feed-bar carries a stud 37 upon which is journaled a block 38 slidably fitted within the forked free end of an arm 39 secured upon the feed-lift rock-shaft. By reason of this location and arrangement of the lifter fork and stud (which is the reverse of that commonly employed, the fork usually being formed as a part of the feed-bar and the stud usually being carried by an arm on the feed-lift shaft) greater clearance is afforded in the region of the loop-taker, thereby rendering it more convenient to withdraw the bobbin-case for the insertion and removal of bobbins.

The feed-drive rock-shaft 32 and the feed-lift rock-shaft 33 are actuated from eccentrics 40 and 41 carried by the main shaft 7 through the medium of pitmans 42 and 43 connected to rock arms 44 and 45 carried, respectively, by the shafts 32 and 33.

Secured to the under side of the base 1 is the casing 46 of an oil pump O which draws oil from a reservoir, formed in a pan on which the machine is normally supported, and forces the oil through suitable conduits to the various bearings throughout the machine. This pump is actuated by a vertically arranged shaft 47, journaled in the pump casing and driven from the bevel gear 20 by a mating bevel gear 48.

As hereinbefore stated, this invention has as an object to improve the sewing qualities of high speed lock-stitch sewing machines. This has

been attained by a novel construction and arrangement of parts now to be described. Referring particularly to Figs. 3 and 6 it will be seen that, in accordance with the present invention, 5 the shaft 9, and therefore the axis of rotation of the loop-taker, is arranged in a plane a substantially to one side of and parallel to a plane b, which latter plane is normal to the work-supporting surface of the machine and passes through the needle-hole in the throat-plate. This places the thread-guiding aperture 49, 10 through which the bobbin thread t emerges from the bobbin-case c', only slightly to the rear of the rear wall 50 of the needle-hole n. With this arrangement the bobbin thread extends more 15 nearly vertically from the aperture 49 to the needle-hole than it does in prior machines. Therefore, during the feed of the work, the bobbin thread is not snubbed about the wall 50 to the extent or with the pressure that it is snubbed in prior machines. Because of this reduced snubbing action, and reduced pressure of the bobbin-thread on the wall 50, the feed of the work is facilitated, thereby producing more uniform sewing 20 and enabling the needle-thread loop to be more readily pulled up between the bobbin thread and the wall 50 during the tightening of the stitch. Likewise this reduction in pressure between the bobbin thread t and the wall 50 greatly 25 reduces the sawing action between the needle and bobbin threads.

To maintain the most desirable relation between the needle and the loop-taker, that is, with the needle reciprocating in a plane intersecting 30 the axis of the loop-taker, the needle-bar has been tipped backwardly away from the front edge f of the work-plate. This causes the needle to be reciprocated in a plane c (Fig. 6) diagonally through the work w, needle-hole n and directly 35 toward the axis of the loop-taker. Preferably, as shown in Fig. 3, this inclination of the needle-bar, and the needle carried thereby, is attained by tipping the entire bracket-arm rearwardly relative to the work-support, but obviously similar 40 results may be obtained by merely tipping the bracket-arm head or by arranging the needle-bar at an inclination in a conventional vertical bracket-arm head.

Inclination of the entire bracket-arm is particularly advantageous in that it affords better visibility at the stitching point, minimizes interference with the operator in handling the work and materially reduces the likelihood of having the operator's head contact parts of the sewing 45 machine, even when she is closely scrutinizing the work at the stitching point.

While the distance which the axis of the loop-taker is offset from the plane b, passing through the center of the needle-hole, may vary, as may 50 also the inclination of the plane c in which the needle reciprocates, it has been found that excellent results are obtained by offsetting the loop-taker approximately .160 of an inch and inclining the plane of reciprocation of the needle about 55 eleven degrees.

Having thus set forth the nature of the invention, what I claim herein is:

1. In a sewing machine having a work-support provided with a needle-aperture, in combination, 70 an endwise reciprocatory needle operating through said needle-aperture, means for reciprocating said needle, work-feeding means, a loop-taker disposed below said work-support for rotation about an axis transverse to the line of feed of the work, said axis being disposed in a plane

spaced in the line of feed from a parallel plane containing said needle-aperture and normal to said work-support, and a bobbin-thread carrier journaled in and restrained against rotation with said loop-taker, said thread-carrier having bobbin-thread delivery means disposed at the needle-aperture side of said plane which contains the axis of rotation of said loop-taker.

2. In a sewing machine having a horizontally disposed work-support provided with a needle-aperture, in combination, an endwise reciprocatory needle operating through said needle-aperture, means for reciprocating said needle, work-feeding means, a loop-taker disposed below said work-support for rotation about an axis transverse to the line of feed of the work, said axis being disposed in a vertical plane at one side of a parallel plane containing said needle-aperture, and a bobbin-thread carrier journaled in and restrained against rotation with said loop-taker, said thread-carrier having bobbin-thread delivery means disposed at that side of the thread-carrier toward which the beak of the loop-taker moves in its loop-taking movement.

3. In a sewing machine having a horizontally disposed work-support provided with a needle-aperture, in combination, an endwise reciprocatory needle operating in an inclined plane through said needle-aperture, means for reciprocating said needle in said plane, work-feeding means, a loop-taker disposed below said work-support for rotation about a horizontal axis transverse to the line of feed of the work, said axis being disposed in a vertical plane forwardly of a parallel plane containing said needle-aperture, and a bobbin-thread carrier journaled in and restrained against rotation with said loop-taker, said thread-carrier having bobbin-thread delivery means disposed at that side of the thread-carrier toward which the beak of the loop-taker moves in its loop-taking movement.

4. In a sewing machine having a horizontally disposed work-support provided with a needle-aperture, in combination, an endwise reciprocatory needle operating in a downwardly and forwardly inclined plane through said needle-aperture, means for reciprocating said needle in said plane, work-feeding means, a loop-taker disposed below said work-support for rotation about an axis transverse to the line of feed of the work, said axis being disposed in a vertical plane forwardly of a parallel plane containing said needle-aperture, and a circular bobbin-thread carrier journaled in and restrained against rotation with said loop-taker, said thread-carrier having bobbin-thread delivery means disposed rearwardly of the last named plane a distance substantially less than the radius of said thread-carrier.

5. In a sewing machine having a horizontally disposed work-support provided with a needle-aperture, in combination, an endwise reciprocatory needle operating in an inclined plane through said needle-aperture, means for reciprocating said needle in said plane, a loop-taker disposed below said work-support for rotation about a horizontal axis, said axis being disposed in a vertical plane forwardly of a parallel plane containing said needle-aperture, work-feeding means including a feed-drive rock-shaft having an upstanding arm, a feed-lift rock-shaft having a laterally extending fork, a feed-bar having its rear end pivotally connected to the arm on said feed-drive rock-shaft and its forward end slidably connected with the fork on said feed-lift

rock-shaft forwardly of the forward periphery of said loop-taker, a feed-dog carried by said feed-bar, and a bobbin-thread carrier journaled in and restrained against rotation with said loop-taker, said thread-carrier having bobbin-thread delivery means disposed at that side of the thread-carrier toward which the beak of the loop-taker moves in its loop-taking movement.

6. In a sewing machine having a horizontally disposed work-support provided with a needle-aperture, in combination, an endwise reciprocatory needle operating in a downwardly and forwardly inclined plane through said needle-aperture, means for reciprocating said needle in said plane, a loop-taker disposed below said work-support for rotation about a horizontal axis, said axis being disposed in a vertical plane forwardly of a parallel plane containing said needle-aperture, work-feeding means including a feed-drive rock-shaft journaled adjacent the rear of said work-support and having an upstanding arm movable only between a vertical plane extending lengthwise of said rock-shaft and a plane inclined rearwardly therefrom, a feed-lift rock-shaft journaled adjacent the front of said work-support and having a fork extending rearwardly toward the axis of rotation of said loop-taker but terminating forwardly of the periphery of the loop-taker, a feed-bar having its rear end pivotally connected to the arm of said feed-drive rock-shaft and its forward end slidably connected with said fork, a feed-dog carried by said feed-bar, and a circular bobbin-thread carrier journaled in and restrained against rotation with said loop-taker, said thread-carrier having bobbin-thread delivery means disposed rearwardly of the last named plane a distance substantially less than the radius of said thread-carrier.

7. In a lock-stitch sewing machine having a horizontally disposed work-support provided with a needle-aperture, work-feeding mechanism, a reciprocatory needle operating through said needle-aperture, a rotary hook complementary to said needle in the formation of lock-stitches, and means for rotating said rotary hook about an axis offset from a vertical plane containing said needle-aperture and transverse to the line of feed, said needle having a path of movement in a line substantially intersecting the rotation-axis of said loop-taker.

8. A sewing machine having a work-supporting surface provided with a needle aperture, an inclined reciprocatory needle-bar located at one side of a plane normal to the work-supporting surface and passing through the center of said aperture, and a rotary loop-seizing member having its axis of rotation located on the opposite side of said plane.

9. A sewing machine having a work-supporting surface provided with a needle aperture, an inclined reciprocatory needle-bar, and a shaft carrying a loop-taker operable about a fixed axis, said needle-bar and the loop-taker axis being located on opposite sides of a plane normal to the work-support and parallel to said shaft, said plane passing through said needle aperture.

10. A sewing machine having sewing instrumentalities including an eye pointed needle and a rotary hook having a loop-seizing beak traveling in a vertical circular path in a counterclockwise direction as viewed from the open face of the hook, and means for reciprocating the needle to cause it to present a thread-loop to the hook-beak, said needle being so disposed with respect to said rotary hook that it presents the thread-

loop to the hook beak, while said beak is travelling from its highest to its lowest vertical positions.

11. A lock-stitch sewing machine comprising a work-support provided with a needle-aperture, work-feeding mechanism, a reciprocatory needle operating through said needle-aperture, a rotary loop-taker complemental to said needle in the formation of lock-stitches, and means for rotating said loop-taker about an axis offset from a plane normal to the work-support and containing said needle aperture and which plane extends transverse to the line of feed.

12. A lock-stitch sewing machine comprising a work-support provided with a needle aperture, work-feeding mechanism, a reciprocating needle operating through said needle aperture in a plane inclined to a plane normal to said work-support and containing said needle aperture and transverse to the line of feed, and a rotary loop-taker located at the under side of said work-support and cooperating with said needle in the formation of lock-stitches, said loop-taker having its axis of rotation located at that side of said plane normal to said work-support at which the point of the needle is located when in its lowermost position.

13. A sewing machine having sewing instrumentalities including an eye-pointed needle reciprocating in a fixed path, and a rotary hook having a loop-seizing beak travelling in a vertical circular path, and means for reciprocating the needle to cause it to present a thread-loop to the hook beak, said needle being so disposed with respect to said rotary hook that it presents the thread-loop to the hook-beak while said beak is travelling between its highest and lowest vertical positions.

14. In a sewing machine having a work-support provided with a needle-aperture, in combination, a reciprocatory needle, a feed-dog operating through said work-support, a feed-advance rock-arm disposed below said work-support, a feed-bar pivotally connected to said rock-arm and carrying said feed-dog, a feed-lift rock-arm having a fork directed toward said feed-advance rock-arm, operative connections between said fork and said feed-bar for imparting work engaging and releasing movements to said feed-dog, a rotary loop-taker complemental to said needle in the formation of lock-stitches, said loop-taker having a thread-loop seizing beak rotatable in a plane normal to said work-support, a thread-carrier journaled in and restrained against rotation with said loop-taker, and a rotary loop-taker carrying shaft having its axis of rotation offset from a plane containing said needle-aperture, which plane is

normal to said work-support and transverse to the line of feed.

15. In a sewing machine having a work-support provided with a needle-aperture, in combination, a reciprocatory needle, a feed-dog operating through said work-support, a feed-advance rock-arm disposed below said work-support, a feed-bar pivotally connected to said rock-arm and carrying said feed-dog, a feed-lift rock-arm having a fork directed toward said feed-advance rock-arm, operative connections between said fork and said feed-bar for imparting work engaging and releasing movements to said feed-dog, a rotary loop-taker complemental to said needle in the formation of lock-stitches, said loop-taker having a thread-loop seizing beak rotatable in a plane normal to said work-support, a thread-carrier journaled in and restrained against rotation with said loop-taker, and a rotary loop-taker carrying shaft having its axis of rotation disposed at the feed-lift rock-arm side of a plane containing said needle-aperture, which plane is normal to said work-support and transverse to the line of feed.

16. In a sewing machine having a bracket-arm head and a work-support provided with a needle-aperture, in combination, a reciprocatory needle, a feed-dog operating through said work-support, a feed-advance rock-arm disposed below said work-support and having a path of movement wholly rearwardly of a plane normal to said work-support and extending in the direction of the axis of oscillation of said rock-arm, a feed-bar pivotally connected to said rock-arm and carrying said feed-dog, a feed-lift rock-arm having a fork directed toward said feed-advance rock-arm, operative connections between said fork and said feed-bar for imparting work engaging and releasing movements to said feed-dog, a spring-depressed presser-bar mounted in said bracket-arm head and upwardly inclined rearwardly, a presser-foot carried by said presser-bar and having a sole portion bearing flatwise on said work-support, a rotary loop-taker complemental to said needle in the formation of lock-stitches, said loop-taker having a thread-loop seizing beak rotatable in the plane normal to said work-support, a thread-carrier journaled in and restrained against rotation with said loop-taker, and a rotary loop-taker carrying shaft having its axis of rotation disposed at the feed-lift rock-arm side of a plane containing said needle-aperture, which plane is normal to said work-support and transverse to the line of feed.

ANDREW B. CLAYTON.
